UNITED STATES PATENT OFFICE.

JOHN J. O'CONNOR, OF BRIDGEPORT, CONNECTICUT, ASSIGNOR TO FITZ-EMPIRE DOUBLE PIVOT LAST COMPANY, OF AUBURN, MAINE, A CORPORATION OF MAINE.

SHOE FORM.

Application filed August 1, 1923. Serial No. 655,093.

This invention relates to shoe forms or stretchers, and is illustrated as embodied in a form of the light adjustable type intended to be placed in a shoe to preserve its shape during the periods when it is not being worn.

It is commercially important that such forms be inexpensive and, in order to secure the requisite quantity production of each size of form, the number of different sized articles corresponding to a line of sizes and widths of shoes must be very small. Accordingly, and in order that the use of such form may be economical for the purchasers, the same form should serve for numerous different sizes and styles of shoes. In view of these considerations, such a form should be adjustable for length and is therefore usually provided with an expandable forepart which is operated by throwing down a longitudinally expanding toggle which unites the forepart and the heel part. The length adjustment is advantageously secured by making this toggle adjustable in length and many such constructions have been suggested, all of which have given trouble in that the adjusting devices have been too complicated to be easily managed by the ordinary non-mechanically inclined individual.

It is accordingly an object of the present invention to meet this difficulty by providing an adjustable toggle mechanism which is simple, cheap and easily operated without possibility of accidents, and to this end an important feature of the invention comprises two toggle links with an adjustable pivot, arranged to break the pivotal connection and permit its readjustment by a mere relative twisting of the links.

Another feature of the invention consists in the provision of a clamping spring preferably encircling the toggle links and holding them together. This readily permits separation of the links to alter the pivotal adjustment by mere manipulation of the links themselves.

These and other features of the invention, including certain combinations and arrangements of parts, will be understood from the following description of a preferred embodiment thereof selected for purposes of illus-

tration and shown in the accompanying drawings in which,

Fig. 1 is a side elevation.

55

Fig. 2 is a front elevation.

The forepart 10 is formed in any desired or convenient manner and is herein shown as made with two toe pieces 12 separable by two toggle links 14, one of which is pivoted in each toe piece, and which are pivoted at their rear ends at 16 to the member 17, which slides in a slot in the toe pieces.

To this member 16 is pivoted the forward toggle link 18. The rear toggle link 20 is mounted in the heel member 22. One of these preferably flat toggle links, as 20, is provided with a series of seats, shown as holes 24, and the other link carries a pivot pin 26. This pin, in the embodiment shown, is not integral with the link 18, but is mounted in a spring clip 28, of generally U-shaped form, arranged to embrace the links and hold them resiliently side by side, with the pivot pin 26 extending through each link. The leg of the clip 28 which does not carry the pin has a hole 30 opposite the pin in which the end of the pin may seat.

It is obvious that the pin 26 can be disengaged from the hole 24 by relatively twisting the toggle links as shown in Fig. 2, and the link 20 can be slipped back and forth to bring a different hole 24 into registration with the pin. In order to guide the sliding link and to prevent its snapping out of engagement with the other link and the clip, the clip may have lugs 32 struck up on it and its lower edge 34 may be bent over to form a channel or guide for the sliding link 20. A lug 36 on the link 20 keeps it from being pulled out lengthwise.

The pivot at 16 is sufficiently high so that the pin 26 will pass its dead center as the links are pressed down into a shoe, as is well understood by those acquainted with this type of devices.

Thus I have provided a toggle mechanism that has only three parts and which can be adjusted by merely twisting the two links upon each other.

Having thus described my invention, what I claim as new and desire to secure by Letters Patent of the United States is:—

1. A shoe form having forepart and heel

members and an adjustable toggle joining the said members comprising two pivoted links lying side by side and arranged to break their pivotal connection when relatively twisted about the longitudinal axis of one of said links to permit readjustment of the pivotal connection.

2. A shoe form having forepart and heel members and an adjustable toggle joining the said members comprising two flat pivoted links lying side by side and arranged to break their pivotal connection when relatively twisted about the longitudinal axis of one of the links and to permit readjustment of the pivotal connection while held in such relatively twisted position.

3. A shoe form having forepart and heel members and an adjustable toggle joining the said members comprising two flat pivoted links, a pivot pin carried by one link and extending into the other, but separable therefrom when the links are relatively rotated on their longitudinal axes, and resilient means for holding the links side by side.

4. A shoe form having forepart and heel members and an adjustable toggle joining the said members comprising two links, a pivot adjustably connected with one of the links and joining them, and a U-shaped compression spring arranged to press against the flat sides of the links for holding the links and pivot in operative position.

5. A shoe form having forepart and heel members and an adjustable toggle joining the said members comprising two flat links each connected to one of said members and lying loosely side by side, one of the links having a series of seats, a pivot pin extending through the other link and arranged to engage in a selected one of the seats and a resilient member extending around both links and clamping them in the vicinity of the pivot.

6. A shoe form having forepart and heel members and an adjustable toggle joining the said members comprising two flat links each connected to one of said members and lying loosely side by side, one of the links having a series of holes, a pivot pin extending through the other link and arranged to engage in a selected one of the holes and a resilient member normally contacting with the outside faces of the links in the vicinity of the pivot and arranged to be spread by twisting one of the links to permit adjustment of the pivot.

7. A shoe form having forepart and heel members and an adjustable toggle joining the said members comprising two flat links, one connected to each of said members, a pivot pin in one of the links, the other link having a plurality of possible engagemental relations with said pivot pin, and a U-shaped spring clip grasping the two links between its ends and connected with the pivot-carrying link near the pivot.

8. A shoe form having forepart and heel members and an adjustable toggle joining the said members comprising two flat links, one connected to each of said members, a U-shaped spring carrying a pivot pin at one of its ends and embracing the flat links between its ends, the links being perforated to accommodate the pivot pin, and one of the links having a plurality of possible engagemental relations with the pivot pin.

9. A shoe form having forepart and heel members and an adjustable toggle joining the said members comprising two flat links lying loosely side by side, a pivot pin carried by one link and extending into one of a plurality of pockets in the other link, and a resilient member holding the links together and arranged to yield as the links are relatively twisted to free the pivot pin from its pocket and permit its adjustment to another pocket.

10. A shoe form having forepart and heel members and an adjustable toggle joining the said members comprising two flattened links lying side by side, a resilient clip embracing them and having a guiding channel formed between its ends in which one of the links may slip and arranged so that its ends may be sprung apart by relatively twisting the links, and a pivot pin extending through the links in their normal operative position, and carried out of engagement with one of the links when they are so relatively twisted.

11. A shoe form having forepart and heel members and an adjustable toggle joining the said members comprising a pair of flattened toggle links, a resilient clip having flattened ends clasping them together, one end of the clip having projecting portions forming a channel through which the associated link may slide, the other end of the clip carrying a pivot pin extending through the other link and into the former named link.

In testimony whereof I have signed my name to this specification.

JOHN J. O'CONNOR.
